ROBERT P. RAMSEY, OF DULUTH, MINNESOTA, ASSIGNOR TO CLYDE IRON WORKS, OF DULUTH, MINNESOTA, A CORPORATION OF MAINE.

CABLEWAY-SKIDDING MACHINE.

Application filed August 22, 1924. Serial No. 733,486.

In conveying systems known as cableway skidders, such as are employed for example in transporting logs in logging operations and the like, it has long been customary to use a trolley running back and forth on a tight line stretched between two elevated points of support, the log or like article being hauled up to such trolley and the latter being then hauled in to one end of such tight line. For the purpose of pulling the trolley out, a so-called out-haul cable or line is required in addition to the in-haul cable, the latter serving the dual purpose of elevating or lifting the log to the trolley and then pulling the trolley in in the fashion just referred to. A third line or cable is likewise required where the in-haul cable is employed to perform such dual function, such third cable being called a slack pulling line since its purpose is to take the slack out of the in-haul cable when the trolley is hauled out and a fresh log is to be picked up. For the purpose of operating the aforesaid out-haul, in-haul and slack pulling lines, a suitable engine with corresponding winding drums, one for each line, and known in the trade as a skidding machine, is employed.

In such skidding machines it has furthermore been the practice for sometime past to provide means for interlocking the in-haul and out-haul drums so that after the log has been raised, it will require no further expenditure of power to sustain the dead weight, power being required merely to pull or haul the log in to the loading station. It will be understood, in other words, that if these drums were not thus intergeared, the out-haul drum would have to be braked and thereby waste energy in amount substantially equal to the load imposed on the in-haul drum by the weight of the article being hauled in.

Despite the marked improvement effected in the operation of cableway skidding systems by thus intergearing the in-haul and out-haul drums, a serious operative difficulty has nevertheless remained. Obviously when the trolley is at the outer end of the span which it covers, the out-haul drum will have on it an amount of cable equal to the length of the span and this materially increases the effective diameter of said drum at which the cable is coiled, while at the stage of operation in question, the in-haul drum will be substantially empty of cable. On the contrary, when the trolley is at the inner end

of the span, the condition in question will be reversed, the out-haul drum now being nearly empty, while the in-haul drum has wound on it an amount of cable equal to the length of the span which materially increases the effective diameter of such drum at which the in-haul cable is coiled when compared with the empty state of said drum. It will accordingly be seen that the varying amounts of cable on these two drums will vary the diameters at which the out-haul and in-haul lines are being coiled and consequently vary the speed at which the cables or lines are being coiled, even though the engine that operates the drum is running at a uniform speed. The result will be to cause the log to raise or lower at an increasing rate, depending upon the varying differential between the diameters of the two drums in question, and in cableway skidding systems, as at present constructed and operated, it accordingly is necessary while a log is being hauled in over the outer portion of the span to stop winding out the out-haul cable, which is being payed out too rapidly, until the in-haul cable can again raise the log to the proper height, whereupon the two drums may be again intergeared and the normal operation resumed, only, however, to be interrupted by the recurrence of the condition just described. At the mid-point in the span only will the two drums pay out and wind in their respective cables at approximately the same rate. On the other hand, in passing over the inner half of the span, the log will be unduly elevated and jam against the trolley unless the in-haul drum be stopped and the out-haul line payed out the proper amount. This likewise may have to be done a number of times in the case of a long span, with the result that considerable delay is incurred in hauling in a log and there is of course a waste of power every time the line has to be readjusted.

One principal object of the present invention, accordingly, is to provide a skidding machine in which the in-haul and out-haul lines may at all times be intergeared or interlocked together, whatever the length of span covered by the trolley operated by such machine. Briefly stated, this result is accomplished by providing means for intergearing the drums in question together in different ratios. As a result, it is unnecessary to interrupt the operation of the machine and

there will be no waste of power due to raising up or dropping the log at intervals as it is being hauled in. The speed of operation as a whole will likewise be measurably increased due to the elimination of delays incident to thus stopping the trolley in order to raise or lower the log.

To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings:—

Fig. 1 is a side elevation of a cableway skidding system equipped with my present improved skidding machine; Fig. 2 is a plan view of such machine on a larger scale; and Fig. 3 is a broken side elevation of the same, likewise on a larger scale.

The arrangement of the lines or cables in the system illustrated in Fig. 1 is more or less typical. Thus the tight line 1, on which the trolley 2 is designed to run, is stretched at a suitable elevation between two trees 3, 3, being tied to the one at the right and passing over a sheave 4 on the other to suitable securing means (not shown) at the left. For the purpose of guiding the several operating lines from the skidding machine 5 to the trolley, a series of sheaves 6, 7 and 8, are attached to the nearer support 3, directly below the sheave 4 thereon. The out-haul line 9 passes over the first of these sheaves to the further end of the span where it is passed around a sheave 10 secured to the farther support 3 and brought back and attached to the trolley. The in-haul line 11 passes over sheave 7 and thence over a pulley block 12, suspended from the trolley, the outer end of said line being equipped with a pair of tongs 13, or equivalent grappling device, adapted to be secured to the log 14 or other article to be transported. A slack pulling line 15 passes over the third sheave 8 and thence out to the trolley where it passes around a sheave 16 and is brought back parallel with in-haul line 11, to which it is fixedly attached at a point 17.

The skidding machine 5, that is provided for operating the lines 9, 11 and 15, principally comprises a corresponding series of winding drums 9^a, 11^a and 15^a, to which the inner ends of the lines in question are respectively attached. As shown in Figs. 1 and 3, the two first-named drums 9^a and 11^a are arranged to wind the corresponding cables up when rotated in a counter-clockwise direction, while the third drum 15^a winds up its cable when rotated in a clockwise direction. While a steam engine 20 is shown as

the source of power for operating these winding drums, it will of course be understood that any suitable motor may be substituted, such engine or motor being suitably connected to rotate the crank shaft 21. Fixed on the latter is a pinion 22 that engages a gear 23, normally loosely rotatable on the shaft 24 that carried drum 11^a. Gear 23 in turn meshes with a corresponding gear 25 that is normally loosely rotatable on the shaft 26 that carries drum 9^a. Fixed on the opposite end of crank shaft 21 is a second pinion 27 which engages a gear 28, normally freely rotatable on the corresponding end of drum shaft 24. This pinion 27 also engages a gear 29 that is normally freely rotatable on the corresponding end of drum shaft 26.

It will be understood that not only are gears 23, 25, 28 and 29 loose and free to run on their respective shafts, but so also are the drums 9^a and 11^a. Each of the gears in question carries a friction block that fits into a complementary friction groove in the adjacent end of the corresponding drum, as need not be described in detail, whereby any selected one of said gears by being thrust endwise against the adjacent drum end will be interlocked therewith. For the purpose of thus thrusting the gears into interlocking engagement with their drums, corresponding steam thrust cylinders 23^a, 25^a, 28^a and 29^a, are provided on the respective ends of shafts 24 and 26. Drums 9^a and 11^a are each provided with cylindrical braking surfaces 9^b and 11^b, respectively, wherewith co-operate suitable brake bands (not shown) by means of which the corresponding drum may be held stationary when desired. For the purpose of driving drum 15^a, a gear 30 in mesh with gear 23 is provided, such gear 30 being normally freely rotatable on the shaft 31 that carries said drum. This gear, like the others just described, is adapted to be interlocked with its drum by suitable thrust mechanism (not shown) when desired.

In order to pull the unloaded carriage or trolley 2 out to desired point on the span, gear 29 is thrust against out-haul drum 9^a so as to cause the latter to rotate in a counter-clockwise direction and thereby pull in the out-haul line which will in turn draw the carriage 2 out to the far end of the span if desired.

From the foregoing description of the manner in which the several drums are interlocked with each other and with the crank shaft 21, it will be seen that the in-haul drum 11^a can be made to rotate in a counter-clockwise direction by thrusting gear 23 into engagement therewith, the speed of such rotation being determined by the ratio of pinion 22 to such gear. It will also be seen that this drum may be made to rotate in the same direction by thrusting gear 28 against its opposite end, the speed of rotation in this case

being greater owing to the fact that gear 23 is larger than gear 28 and pinion 22 is smaller than pinion 27. This drum therefore can be rotated in a counter-clockwise direction at 5 two different speeds which may be called high speed and low speed for the purpose of distinction.

Out-haul drum 9^a can be rotated at a certain speed in a clockwise direction by thrusting gear 25 thereagainst, and in a counter-clockwise direction at a greater speed by thrusting gear 29 against its opposite end, gear 25 being larger than gear 29, and pinion 22, which drives said gear 25 through gear 23, 10 being smaller than pinion 27. When it is desired to use slack pulling line drum 15^a, the brake is held on out-haul drum 9^a and gear 30 is thrust into engagement with said drum 15^a, as a result of which the latter will be rotated in a clockwise direction and pull in the slack pulling line. The effect of pulling in such line will be to cause the outer end of the in-haul line to slack beyond pulley block 12 15 towards the ground.

25 By way of general description of the operation of the system, assuming the trolley or carriage 2 to be in the air directly above a log that is to be skidded, the slack pulling line drum 15^a will be operated in the manner just explained to bring the end of the in-haul cable 11 to within reach of the log. It is then suitably fastened thereto by means of the tongs 13 or equivalent device. The out-haul line 9 is now held stationary by means of the 30 brake on drum 9^a and gear 23 is thrust against the in-haul drum 11^a which winds up the in-haul line 11 and causes the log to be raised up toward the trolley or carriage. When the log is elevated to the proper height, gear 25 is engaged with the out-haul drum and the brake on 35 said drum simultaneously released. As a result, the in-haul and out-haul drums will be geared together and the out-haul line will be paid off the drum at the same time that the in-haul line is wound up. As the operation is 40 continued, these two lines are respectively paid out and pulled in at certain relative speeds, the speed of the line going out being somewhat greater than that of the line coming in so that the log will gradually lower 45 away from the carriage.

Whenever the log becomes sufficiently low so that it is in danger of dragging on the ground, gear 23 is released from the in-haul drum and gear 28 engaged therewith instead. It will be understood that the standard means provided for thus engaging these gears with the drum, such as the thrust cylinders shown, 50 may be so arranged that the change in question can be made practically instantaneously, that is, the gear 28 will be engaged with the drum the moment gear 23 is released and vice versa. As a result of this last mentioned shift of gears, the in-haul drum 11^a will be rotated at its high speed and thereby wind in

the corresponding line faster, the arrangement in fact being such as to cause its line to be thus wound in faster than the out-haul line is going out. As a result the log will gradually rise again as the carriage travels 55 along the tight line, and if this condition were permitted to continue, the log would eventually jam against the carriage. Before this can occur, however, the gear 28 is disengaged from and the gear 23 engaged with the in-haul 60 drum so as to restore the first described condition.

It will be seen from the foregoing that a log suspended from the in-haul line under the carriage and being brought towards the loading station can be raised or lowered at the will of the operator by thus engaging and disengaging the gears in question with the in-haul drum. It will be noted further that the speed of travel of the carriage is controlled 65 entirely by the rate at which out-haul line 9, which is fastened at its outer end to such carriage, is paid off of drum 9^a. The result, therefore, of applying high or low speed drive to in-haul drum 11^a is to cause the log to 70 gradually be raised or lowered under the carriage in its travel towards the machine, as just set forth.

While I only show two speeds for the in-haul drum, it will be understood that if for 75 any reason it should be found desirable to increase the number of speed changes in the mechanism for driving this drum, this may be readily accomplished. With this arrangement the operator is enabled to run his engine at full speed continuously and still control the elevation of the log very easily by simply changing the drive from the in-haul drum from high to low speed or vice versa, 80 these changes being made instantaneously and without shock to machinery or lines. Furthermore, the in-haul and out-haul drums being at all times interlocked or geared together, none of the advantages of the intergeared system are lost nor is there any waste 85 of power involved in adjusting the elevation of the log by my improved arrangement since the downward movement by correspondingly relieving the load on the in-haul cable will 90 make up for the energy required again to elevate the log.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. The combination with a power driven shaft; two drum-shafts parallel therewith; in-haul and out-haul drums mounted on said drum-shafts, respectively, and normally free- 120 ly rotatable with respect thereto; two gears on 125

each of said drum-shafts, respectively, said gears being likewise normally freely rotatable and one pair thereof intermeshing; means adapted to fix said gears to the corresponding drums as desired; a pinion fixed on said drive-shaft and meshing with the one of said intermeshing gears corresponding with said in-haul drum; and a second pinion fixed on said drive-shaft and meshing with both of the other pair of said gears, the gear ratios of the respective sets of gears whereby said drums may thus be rotated by said drive-shaft being different.

2. The combination with a power driven shaft; two drum-shafts parallel therewith; in-haul and out-haul drums mounted on said drum-shafts, respectively, and normally freely rotatable with respect thereto; two gears on each of said drum-shafts, respectively, said gears being likewise normally freely rotatable and one pair thereof intermeshing; means adapted to fix said gears to the corresponding drums as desired; a pinion fixed on said drive-shaft and meshing with the one of said intermeshing gears corresponding with said in-haul drum; and a second pinion fixed on said drive-shaft and meshing with both of the other pair of said gears, the gear ratios of such last-mentioned set of gears being such as to rotate said in-haul drum more rapidly relatively to said out-haul drum than said first-mentioned set of gears.

3. The combination with a power driven shaft; two drum-shafts parallel therewith; in-haul and out-haul drums mounted on said drum-shafts, respectively, and normally freely rotatable with respect thereto; two gears on each of said drum-shafts, respectively, said gears being likewise normally freely rotatable and one pair thereof intermeshing;

means adapted to fix said gears to the corresponding drums as desired; a pinion fixed on said drive-shaft and meshing with the one of said intermeshing gears corresponding with said in-haul drum; a second pinion fixed on said drive-shaft and meshing with both of the other pair of said gears, the gear ratios of the respective sets of gears whereby said drums may thus be rotated by said drive-shaft being different; a third shaft; a slack pulling line drum normally freely rotatable thereon; and means adapted to intergear said last named drum with one of said intermeshing pair of gears.

4. The combination with a power driven shaft, two drum-shafts parallel therewith; in-haul and out-haul drums mounted on said drum-shafts, respectively, and normally freely rotatable with respect thereto; two gears on each of said drum-shafts, respectively, said gears being likewise normally freely rotatable and one pair thereof intermeshing; means adapted to fix said gears to the corresponding drums as desired; a pinion fixed on said drive-shaft and meshing with the one of said intermeshing gears corresponding with said in-haul drum; a second pinion fixed on said drive-shaft and meshing with both of the other pair of said gears, the gear ratios of the respective sets of gears whereby said drums may thus be rotated by said drive-shaft being different; a third shaft; a slack pulling line drum normally freely rotatable thereon; and means adapted to intergear said drum with the one of said intermeshing pair of gears corresponding with said in-haul drum.

Signed by me this 18th day of August, 1924.

ROBERT P. RAMSEY.
